UNITED STATES PATENT OFFICE

165,798

DISPLAY CABINET OR SIMILAR ARTICLE

Abe Shilin, New York, N. Y., and Harry Denworth,
Mount Holly, N. J., assignors to Holly Mills,
Inc., a corporation of New Jersey

Application September 15, 1950, Serial No. 12,202

Term of patent 14 years

(CL. D80—11)

To all whom it may concern:

Be it known that we, Abe Shilin and Harry Denworth, citizens of the United States, residing at the city of New York, county of Bronx, State of New York, and Mount Holly, county of Burlington, and State of New Jersey, respectively, have invented a new, original, and ornamental Design for a Display Cabinet or Similar Article, of which the following is a specification, reference being had to the accompanying drawing, forming part thereof.

The figure is a perspective view of a display cabinet or similar article showing our new design.

We claim:

The ornamental design for a display cabinet or similar article, as shown.

ABE SHILIN.
HARRY DENWORTH.
